PRESSURE COOKER

Edward J. Nelson, Omaha, Nebr., assignor, by mesne assignments, to Ballantyne Instruments and Electronics, Inc., Omaha, Nebr., a corporation of Delaware

Filed Nov. 14, 1960, Ser. No. 62,803

Term of patent 14 years

(Cl. D81—10)

Fig. 3

Fig. 4

FIGURE 1 is a left front perspective view of a pressure cooker, showing my new design.

FIGURE 2 is a right front perspective view.

FIGURE 3 is a top plan view.

FIGURE 4 is a rear elevational view.

The heavy stippling on the front panel, handles and feet represents contrasting surface areas.

The characteristic features of my new design for a pressure cooker as shown reside in the shape and arrangement of the control panel and in the shape and arrangement of the cooking vessel element together with its cover and cover control.

I claim:

The ornamental design for a pressure cooker, as shown and described.
